UNITED STATES PATENT OFFICE.

WILFRED G. UNGER, OF HAGERSTOWN, MARYLAND, ASSIGNOR OF ONE-HALF TO
CHARLES L. PAGE, OF BALTIMORE, MARYLAND.

INTERNAL-COMBUSTION ENGINE.

Application filed June 19, 1924. Serial No. 721,046.

This invention relates to internal combustion engines, particularly those of the rotary valve type, and has for its principal object the provision of an engine of this character which embodies features of construction and arrangement which will overcome defects existing in known engines of this variety, the improvements involving the application of certain established principles as will be pointed out.

Rotary valve engines of ordinary construction appear to be inherently defective owing to the excessive pressure brought against the rotary valve at certain times in the cycle of movement of the pistons. Naturally, the rotary valve is in such position at the beginning of the working stroke, or at the time of explosion, that the intake and exhaust valves are closed. As a result, there is a tremendous pressure against the valve at the time of the explosion and this pressure operates to bind the valve so closely to the manifold encircled thereby or surrounding it, at least partially, as the case may be, that excessive friction, wear and overheating result. If the relation or fit of these parts be such that the pressure will not cause binding with its attendant or consequent disadvantages, there will be loss of compression and naturally a resulting loss in power accompanied probably by excessive carbonization.

It is with the above facts in view that I have designed the engine constituting the subject-matter of the present application, and the invention has for a more specific object the provision of an engine in which the cylinders, grouped or blocked, as may prove most suitable, are so mounted with respect to the crank case as to be capable of limited lateral or rocking movement and in which the arrangement, relation and area of the inlet and exhaust ports are such that there will be a reaction during the cycle of movement of the pistons which will operate to neutralize, to a certain extent, the above referred to pressure which comes against the rotary valve, and this partial neutralization acts to balance the pressure of the action and the opposing reaction so that the actual pressure against the valve will be reduced to such an extent as to prevent binding of the rotary valve while at the same time the valve will be held

firmly and closely against its manifold and casing so as to prevent any leakage and loss of compression which might otherwise occur.

An important object of the invention is the provision of a peculiar arrangement of the intake and exhaust ports whereby the incoming charge will pass over the pistons and serve to cool them while being warmed by contact therewith, combustibility of the charge of mixture being consequently increased.

Another object of the invention is to provide engine-suction operated lubricating means for the rotary valve, which means includes or is combined with means for reclaiming waste gases in the crank case of the engine and the small volume or quantity of mixture which is imprisoned within the ports of the rotary valve as these ports pass out of and beyond registration with the inlet ports to the cylinders.

The invention further contemplates the general improvement of engines of this class in the matter of detailed construction and arrangement of the parts whereby the structure will be comparatively simple and the operation be made more efficient.

To the attainment of the foregoing and other objects and advantages, the invention consists in the combination and arrangement of parts to be hereinafter more fully described and claimed, and illustrated in the accompanying drawings, it being, however, understood that various changes and modifications may be resorted to as may be found necessary or advisable, provided such variations constitute no departure from the spirit of the invention or the scope of the claims hereunto appended.

In the drawings chosen to illustrate the preferred embodiment of my invention:

Figure 1 is a side elevation of the engine constructed in accordance with my invention, certain of the parts being shown in section.

Figure 2 is a vertical section on the line 2—2 of Figure 1, the direction of view being indicated by the arrows adjacent the ends of said section line.

Figure 3 is a similar view on the line 3—3 of Figure 1, the direction of view being indicated by the arrows adjacent the ends of said section line.

Figure 4 is a section on the line 4—4 of Fig-

ure 1, the direction of view being indicated by the arrows adjacent the ends of said section line.

Figure 5 is an end elevational view, the sleeve valve being shown in cross section.

Figure 6 is a detail horizontal sectional view on the line 6—6 of Figure 1.

Referring more particularly to the drawings, the numeral 1 designates the crank case which is preferably of the usual two-part construction and formed or provided with end bearings 2 for a crank shaft 3 having crank portions 4 corresponding in number to the number of cylinders. Mounted on the crank case are the cylinders designated generally by the numeral 5 and these cylinders may be formed separately or cast en bloc with any desired number in a group, depending upon the total number of cylinders and the preference of the manufacturer. In the ordinary construction the cylinder blocks are rigidly mounted with respect to the crank case but in the present arrangement the crank case is formed with or carries knuckles 6 with which interfittingly engage knuckles 7 on the cylinder blocks, pivotal connection being effected by means of a pintle or rod 8. By so mounting the cylinders or the cylinder blocks, it is apparent that the cylinders are capable of a limited rocking or lateral movement during the cycle of the pistons. The cylinders communicate with the crank case through openings 9 within which are located gaskets or packing rings 10 engaged beneath the cylinders for the purpose of preventing leakage. Operating within the respective cylinders are ordinary pistons 11 carried by connecting rods 12 engaged upon the cranks 4 of the crank shaft.

Formed upon or secured to the crank case so as to be stationary with respect thereto, is a manifold, designated generally by the numeral 13, which is located at a point opposite the upper ends of the cylinders. One end is closed by a wall 14 while the opposite end 15 is open and is connected to the exhaust line. This manifold is arranged with its axis parallel with the crank shaft of the engine. The upper portions or closed ends of the cylinder blocks are formed at one side with a casing section 16 at one side of the manifold, and secured to this section by threaded studs 17 or the like, is a cap 18 which is semi-cylindrical in section and which mates with the section 16 to define a valve casing surrounding the manifold. Slip rings 18^a are provided for permitting longitudinal expansion of the manifold as it becomes heated. If desired, a cover 19 may be provided located outwardly of and in spaced relation to the cap member 18 and secured thereto at its upper edge and to the crank case at its lower edge. At the opposite side of the cylinder blocks there is preferably provided a cover plate 19^a having its upper edge engaging the

blocks, as shown, and its lower edge seating upon or engaged with the crank case, which cover plate is of a more or less spring-like nature. The inner periphery of the valve casing defined by the parts 16 and 18 is formed with a longitudinally extending semi-cylindrical space or passage 20, and at spaced points the outer periphery of the manifold is recessed or undercut so as to form longitudinal passages or spaces 21 arranged at intervals, as shown, all of which communicate through openings 22 with chambers 23 in the ends of the casing section 16. The recessing to define the passages 21 leaves bearing surfaces 21^a. Centrally, the casing defined by the section 16 and cap 18 is formed with a pair of annular chambers 24 separated by a web 25. At this point the casing section 16 is formed with a downward extension 26, and the cap 18 is similarly formed with a downward extension 27 mating with the extension 26 and formed with chambers 28 communicating with the chambers 24, the chambers 28 being separated from each other by a web 29 which may be construed as a continuation of the web 25. Both chambers 28 have a common opening 30 which constitutes the air inlet or intake for the engine carburetor, not shown.

Leading into the chambers 23 are the ends of a pipe 31 which has its intermediate portion 32 located within the crank case and formed with perforations 33 for the purpose of permitting the entrance of gases accumulating within the crank case and also permitting the entrance of oil which is splashed about within the crank case when the engine is in operation. The portion 32 of the pipe has connected therewith an air inlet pipe 34 which extends through and terminates beyond one side of the crank case so as to be in communication with the atmosphere.

The adjacent ends of the spaces or passages 20 and 21 lead to the chambers 24, and to permit free communication, the walls 35 forming the ends of the chambers 24 and the opposite walls of the web 25 are formed with ribs 36 which extend radially therefrom and which define radial passages 37.

The opposite ends of the cap member 18 are formed with extensions 38 adapted for connection with the outlet manifold from a carburetor, not shown, and these extensions are of course chambered, as shown at 39, to communicate with the casing defined by the parts 16 and 18. The manifold 13 is formed with an elongated tubular central portion 40 which has no communication whatever with the chambers 39 and which extends through the end 15 so as to communicate with the exhaust pipe 41 bolted onto this end. The manifold further includes an outer passage 43 which has its ends cut away at 44 for communication with the chambers 39. The manifold is formed opposite each cylinder with two ports 130

45 and 46, which communicate, respectively, with the tubular central portion 40 and the annular passage 43, and these ports register respectively with exhaust and inlet ports 47 5 and 48 in the casing section 16 which of course lead into the cylinders. It will be observed that the closed ends of the cylinder are inclined and extend substantially tangentially with respect to the valve.

10 Each cylinder is equipped with the usual spark plug 49 and the cylinders have their walls formed with passages 50 defining water jackets for cooling purposes, as is customary, suitable inlet and outlet connections or openings 15 51 and 52 being provided at convenient points.

20 Rotatably mounted within the casing defined by the members 16 and 18 and bearing on the uniformly spaced surfaces 21^a are rotary sleeve valves 53 which terminate slightly short of the chambers 23, or at the openings 22. These sleeve valves are formed with ports 25 54 designed to register successively with the ports 45 and 47 and 46 and 48, for controlling the admission of mixture to the cylinders and the exhaust of burnt gases therefrom.

20 Obviously, any suitable means might be provided for rotating the valves, though in the present instance I have shown them as 30 formed at their inner ends with ring gears 55 meshing with gears 56 on a shaft 57 suitably journaled and driven from the crank shaft, as for instance by means of a chain, belt or the like, indicated at 58. As there are 35 three sets of ports 54 in the rotary valve, the ratio between the co-acting drive elements on the crank shaft and shaft 57 is such that the shaft 57, and consequently the valve 53, will turn once for every six revolutions of the crank 40 shaft so that each port 54 in the valve acts first to permit the exhaust of the burnt gases and then to admit a charge of mixture.

45 In the operation, the suction produced by the engine pistons 11 draws fuel mixture from the carbureter through the extensions 38, chambers 39 and annular passages 43 through the ports 46 and ports 48 into the cylinders. Owing to the fact that the inlet ports 48 are below the exhaust ports 47, the inrushing 50 fresh charge will pass over and probably or at least possibly impinge against the piston heads and cool them, the heat from the pistons being communicated to the charge and effecting heating thereof so that the combustibility will be increased. The suction through the carbureter causes a suction 55 through the chambers 28 and 24, through the passages 20 and 21, chambers 23, pipe 32, and air pipe 34. Air enters the pipe 32 through the pipe 34 and splashed oil together with 60 gases accumulating within the crank case 1 enter the pipe 32 through the perforations 33. The air and waste gases are drawn through the pipe 32, through 31, into chambers 23, 65 passages 20 and 21, chambers 24, chambers

28, and outlet 30 to the carbureter, and the splashed oil above referred to follows the same path. Owing to the provision of the passages 20 and 21 in the valve casing and valves, it is obvious that this oil will be 70 uniformly distributed along the bearing surfaces of the manifold, valve and casing so that wear will be reduced to the minimum owing to the efficiency of this system of lubrication. The radial passages 37 in the walls 75 of the chambers 24 insure proper flow. The oil entering the chambers 24 acts to lubricate the intermeshing gears 55 and 56 as well as the other wearing parts. It should also be 80 stated that the small volume of explosive mixture imprisoned within the ports 54 during the rotation of the valves escapes from these ports through the passages 20 and 21 and is returned to the carbureter through the air 85 inlet thereof so that no waste occurs.

90 One of the most distinctive features in the operation of an engine constructed as illustrated and as above described, is the counter-balancing or partial neutralization of the pressure against the rotary valve. When 95 the explosions occur in the various cylinders, the expansion effect produces or tends to produce a tremendous pressure through the intake and exhaust ports against the rotary valve. However, owing to the fact that the 100 cylinders are pivoted for limited rocking or lateral movement, and as the pivot point is at the same side as the manifold, valve, and casing for the latter, the reaction of the valve pressure against the closed ports of the 105 valve will tend to rock the groups or blocks of cylinders upon their pivots away from the valve, thus partly neutralizing and relieving this pressure to such an extent that the remaining pressure of the cylinder against 110 the valve will be only such as to maintain it in a proper close relation to the manifold and casing, thereby avoiding any possibility of undue friction and consequent wear accompanied by overheating. Obviously, the 115 reaction is proportionate to the size or areas of the ports compared with the total area against which the pressure is exerted and it is true that the size of the ports must therefore be predetermined with reasonable accuracy to insure maximum efficiency. Attention is also directed to the fact that the inclination of the end walls of the cylinders with respect to the axes thereof and to the 120 valve, manifold and casing, will assist in the reaction. The actual movement of the cylinders with respect to the crank case and valve is slight as it is intended only to attain the reaction or counter-balancing effect which this produces so as to accomplish the results 125 contemplated.

Having now described my invention, what I claim as new and desire to secure by Letters Patent, is:

1. In an engine, a stationarily mounted 130

- manifold, cylinders pivoted at one side to be capable of lateral movement, a sleeve valve movably mounted with respect to the manifold, and a valve engaging portion carried by the cylinders.
2. In an engine, a stationary manifold, a rotary sleeve valve surrounding the manifold, cylinders, a valve casing carried by the cylinders and surrounding the valve, and means mounting the cylinders for movement with respect to the manifold whereby to accomplish a reaction against the pressure within the cylinders, said means comprising a pivotal mounting for the cylinders at one side of all thereof.
3. In an engine, a stationary manifold, a rotary sleeve valve surrounding the manifold, cylinders, a valve casing carried by the cylinders and surrounding the valve, and means mounting the cylinders for movement with respect to the manifold whereby to permit a reaction against the pressure within the cylinders.
4. In an engine, a crank case, a manifold stationarily mounted with respect thereto, cylinders on the crank case hinged with respect thereto, a valve casing carried by the cylinders and surrounding the manifold, and a rotary sleeve valve within the casing in surrounding relation to the manifold.
5. In an engine, a crank case, a combined intake and exhaust manifold stationarily mounted with respect to the crank case, cylinders hingedly mounted upon the crank case and carrying a valve casing section partially surrounding the manifold, a complementary member carried by said section and cooperating therewith to define a valve casing, and a rotary sleeve valve surrounding the manifold and located within said casing.
6. In an engine, a crank case, cylinders hingedly mounted at one side upon the crank case, a manifold stationarily mounted with respect to the crank case, a casing carried by the cylinders and surrounding the manifold, a rotary valve between the casing and manifold, the cylinders being formed with ports for communication with the manifold.
7. In an engine, a crank case, cylinders hingedly mounted at one side upon the crank case, a manifold stationarily mounted with respect to the crank case, a casing carried by the cylinders and surrounding the manifold, a rotary valve between the casing and manifold, the cylinders being formed with ports for communication with the manifold, the end walls of the cylinders being inclined substantially tangential to the valve.
8. In an engine, a crank case, cylinders thereon, a manifold, a casing carried by the cylinders and surrounding the manifold, the manifold being offset and angularly disposed with respect to the cylinders, the cylinders having ports for communication with the manifold, the ports in each cylinder being ar-
- ranged one above the other and the intake port being lowermost whereby the incoming charge will cool the piston and be heated thereby, and the end walls of the cylinders sloping downwardly from the exhaust ports.
9. In an engine, a crank case, cylinders hinged at one side thereon, a manifold stationarily mounted with respect to the crank case at the same side as the hinge mounting for the cylinders, a casing carried by the cylinders and surrounding the manifold, and a valve movably mounted between the manifold and casing, the cylinders having ports controlled by the valve, the hinge mounting for the cylinders permitting movement thereof away from the manifold to partially neutralize the pressure coming against the valve.
10. In an engine, a crank case, cylinders, a casing carried by the cylinders, a manifold stationarily mounted within the casing, the cylinders having ports for communication with the manifold, a rotary valve between the manifold and casing, the casing being formed with an intermediate chamber, end chambers and passages establishing communication therebetween, the intermediate chamber being adapted for communication with the intake of a carburetor, and a conduit leading from the crank case to said end chambers.
11. In an engine, a crank case, cylinders, a casing carried by the cylinders, a manifold stationarily mounted within the casing, the cylinders having ports for communication with the manifold, a rotary valve between the manifold and casing, the casing being formed with an intermediate chamber, end chambers and passages establishing communication therebetween, the intermediate chamber being adapted for communication with the intake of a carburetor, and a conduit leading from the crank case to said end chambers, said conduit extending along a portion of the crank case and having openings for the entrance of oil and waste gases.
12. In an engine, a crank case, cylinders, a valve casing, a manifold within the valve casing, a rotary valve, chambers at the ends of the casing, a chamber at the intermediate portion of the casing, ducts establishing communication between said chambers, a conduit extending into the crank case and connected with the end chambers for supplying air and oil thereto, the intermediate chamber being adapted for connection with the air inlet of a carburetor.
13. In an engine including a manifold, a valve movably mounted thereabout and a casing surrounding the valve, said manifold being formed with separate compartments one constituting the exhaust and the other the intake, a chamber at the intermediate portion of the casing adapted for connection with the air intake of a carburetor, chambers at the ends of the casing, ducts establishing

communication between the chambers, and means for supplying air and oil to said end chambers.

14. In an engine, cylinders, a manifold divided into exhaust, intake and lubricating compartments, a movably mounted valve surrounding the manifold, a casing surrounding the valve, the ends of the casing being formed with chambers communicating with the ends of the intake compartment and adapted for connection with the mixture outlet of a carbureter, the intermediate portion of the casing being formed with chambers communicating with the lubricating compartments and adapted for connection with the air inlet of the carbureter.

15. In an internal combustion engine, a manifold mounted in operative relation with respect thereto and provided with fuel supply, exhaust and lubricating compartments, said lubricating and fuel supply compartments being so connected that during the operation of the engine air is drawn first through the lubricating compartments and then through the fuel supply compartment.

16. In an internal combustion engine, a stationary manifold, a rotary sleeve valve surrounding the manifold and serving to admit fuel to the engine and exhaust burnt gases therefrom, said manifold being formed with a compartment for said fuel and one for said burnt gases, and an additional compartment opening toward said sleeve valve and serving to lubricate the same, the lubricating means being supplied to said compartment by suction produced by the operation of the engine.

17. In an internal combustion engine, a stationary manifold, a rotary valve surrounding said manifold, cylinders, a valve casing carried by the cylinders and surrounding the valve, said manifold being formed with intake, exhaust and lubricating pas-

sages, said lubricating passages being connected with the crank case of the engine on the one hand and with the intake of the carbureter on the other hand so that when the engine is operated lubricating material is drawn through said lubricating passages.

18. In an internal combustion engine, a stationary manifold, a rotary sleeve valve surrounding the manifold, cylinders, a valve casing carried by the cylinders and surrounding the valve, said manifold being provided with fuel supply and exhaust passages and with complementary passages in the manifold and casing for lubricating the sleeve valve therebetween, said passages being connected with the fuel supply passage and with the crank case of the engine so that when in operation lubricating material is drawn by suction through said lubricating passages.

19. In an internal combustion engine, a stationary manifold, a rotary sleeve valve surrounding the manifold, cylinders, a valve casing carried by the cylinders and surrounding the valve, said manifold being provided with fuel supply and exhaust passages and with lubricating passages opening on the sleeve valve, said lubricating passages being supplied with lubricating material by the suction of the engine which draws air therethrough, said suction also serving to draw and mix with the fuel supply, waste gases from the crank case of the engine and gases trapped within the ports of the sleeve valve.

20. In an internal combustion engine, a stationarily mounted manifold, cylinders pivoted at one side thereof and capable of rocking movement, and a valve movably mounted with respect to the manifold and engaging portions of the cylinders.

In testimony whereof I affix my signature.

WILFRED G. UNGER.
